BINDER AND CUTTER MECHANISM FOR
KNITTING MACHINES

Harry McAdams, Reading, Pa., assignor to The
Nolde and Horst Company, Reading, Pa., a
corporation

Application February 11, 1938, Serial No. 190,065

13 Claims. (Cl. 66—145)

This invention relates to improvements in binder and cutter mechanisms for knitting machines. It is a continuation in part of applications Serial Nos. 730,666, filed June 14, 1934, now Patent No. 2,164,119, and 143,366, filed May 18, 1937.

The primary object of this invention is the provision of an improved binder arrangement for a yarn binding and cutting mechanism of a knitting machine.

10 In the drawing, wherein for the purpose of illustration is shown a preferred embodiment of the invention.

Figure 1 is a perspective view of the improved binder and cutter as mounted upon a knitting machine showing it just prior to a binding and cutting action upon the yarns.

Figure 2 is a view of the binder and cutter showing it with the yarns clamped and bound in it.

20 Figures 3, 4 and 5 are cross sections taken on their respective lines shown in Figures 1 and 2 of the drawing.

Figure 6 is a cross sectional view similar to Figure 5, but showing the arrangement of binders and cutter just prior to the final clamping and cutting action.

25 Figures 7, 8 and 9 show the various positions of the intermediate binder in open and closed positions and with respect to different gauge yarns to be bound thereby.

30 In the drawing, wherein similar reference characters designate corresponding parts throughout the several views, the letter T designates the improved cutter and binder, which is mounted as an attachment upon the latch ring 130 of a knitting machine for the purpose of cutting and binding yarns 93 and 94^a. These yarns are fed respectively by suitable fingers 91 and 92 which may be controlled in the usual manner off of pattern mechanism such as is set forth in my above identified application Serial No. 730,666. While the yarns 93 and 94^a in that machine are located at the auxiliary feed of the knitting machine the improved binder and cutter T may serve its purpose in connection with the severing and binding of any yarns. The yarns 93 and 94^a in the knitting machine of application Ser. No. 730,666 are out of action during knitting of the heel and toe. These yarns may be of different gauges. Thus, 35 yarn 93 may be 36/2 mercerized and yarn 94^a may be 100 denier silk.

40 The improved binder and cutter includes a safety factor in the secure binding of the yarn without injury or liability of breakage thereof which is not found in prior binders and cutters.

The improved binder and cutter consists of a supporting frame 400 fixedly secured upon a block 401 which may be detachably connected to any part of the knitting machine. In the present invention it is connected upon the top of the latch ring. A vertically slidable frame 403 is in turn carried in the frame 400. It has attached thereto to a horizontal bar 405, which is channeled on one side for slidably receiving a reciprocating bar 406. At its inner end the bar 405, which is secured to the vertically slidable frame 403, as by screws 407, shown in Figures 3 and 9, is provided with a depending cutter and binder base bar 410, which is shown in cross section in Figure 5. Portion 410 has a sharp cutter edge 411, 15 and upon its side facing the inner periphery of the latch ring it is provided with a binder groove 412. Upon vertical movement of the slidable frame portion 403 the mounting portions 405 and 410 move therewith. The said parts are limited 20 in their downward movement by an adjustable screw 415, shown in Figure 3, so that the lower cutting and binding end of the cutter and binder mechanism may be lowered or elevated to any desirable level suitable for the purpose for which 25 the cutter and binder mechanism is adapted, in any particular case.

Cutting and binding arms 416 and 417 respectively are pivotally attached upon a pin or shaft 418 at opposite sides of the cutting and binding 30 base portion 410 of the frame. They are movable, scissors-like, with respect to the depending base portion 410, and the cutter arm 416 is provided with a sharp edge 420 cooperating with the edge 411 to sever yarns as the cutter bar 416 is moved from the position shown in Figure 1 to the position shown in Figure 2. The binder arm 417, on the other hand, is provided with a rounded edge 421 in a cooperating relation with an adjacent rounded edge 422 of the bar 410 to squeeze 35 the yarns 93 and 94^a therebetween in a binding relation, in contrast to a cutting action. A spring, shown at 425 in Figure 4 of the drawing, mounted on the pivot pin 418 assists in maintaining the cutting and binding arms 416 and 417 in 40 proper position against the opposite sides of the cutting and binding bar 410. The slide bar 406 is connected at its forward end to the upper ends of the cutter and binder bars 416 and 417 by pin 427, on a fixed axis, so that forward sliding of the bar 406 will open the arms 416 and 417 with 45 respect to the bar 410, and rearward sliding of the bar 406 will enable spring 425 to pull the arms 416 and 417 into cutting and binding relation with the yarns. Normally a cam operated 50

55

lever operated off of suitable pattern mechanism engages pin 440 and holds the bar 406 in forward position, in order to open the binder and cutter bars.

5 An auxiliary binding arm 435 is loosely pivoted upon the pivot pin 418. It has an opening 435a therein which admits of horizontal loose play upon pin 418. Below the pivot 418 it operates in the binder groove 412 of the bar 410 in order to 10 more securely bind the yarns against release, as is shown in Figures 5, 6 and 9 of the drawing. The upper end of the auxiliary binder arm 435 is spring urged at 437 into the binding position shown in Figures 7 and 9 of the drawing. As is 15 shown in Figure 2 the portion of the auxiliary binder arm 435 above the pin 418 is provided with a large opening 436 which will permit the spring 437 to wholly bring about the binding action upon the yarns.

20 It will be noted from Figure 7 of the drawing that the facing surfaces of the binding arm 435 and the bar 410 are relatively sloped, which in cooperation with the loose play which the binder 435 has on its pivot pins enables the binder arm 25 to clamp both coarse and fine yarns. Ordinarily the main binding arm 417 will not clamp the finer of the yarns, due to its spread action, but the other binding arm 435 is enabled to force the coarse and fine yarns into the channel groove of 30 the binder base bar 410, and because of the arrangement of binding surfaces and loose play of the binder arm it will properly clamp these yarns.

It will be particularly noted from Figure 6 of the drawing that the binder arm 435 closes ahead, 35 of the cutter knife 416, and also ahead of the other binder arm 417. This is done to prevent the yarns from back-lashing and getting out of the binder when cut off by the cutter blade.

The loose pivoting of the binder arm 435 enables that arm to be closed without a snap, since the action is not too positive, some motion being lost due to its loose pivoting during return of the binder from its open position shown in Figure 8 to its binding position shown in Figure 9. This 45 eliminates cutting of the yarns.

It should also be noted that the binder arm 417 forces the yarns to a position inside of the needle line. If the binder arm 435 were the only one provided the yarn would be held suspended directly over the heads of the needles and when the 50 yarn clamping finger is put out of action the yarn or yarns would be liable to ride on the heads of the needles for a short space; causing holes to appear in the fabric. With the provision 55 of the binder arm 417, shown in the position in Figure 5, the yarn is held to the inside of the needle line and this enables the yarn feed finger when it goes into action to accurately knife the 60 yarns in proper position between the desired needles.

While this improved binder is desired mostly at the auxiliary feed side of the knitting machine, as shown in my application Serial No. 730,666, it may be used at any desired location and for any 65 binding and cutting purpose. In the feed of heavy and light yarns, one instance where it could be used would be in making a plated stocking on a two-feed machine having a wrap stripe yarn. The heavier yarn 93 would be the lining yarn 70 and the finer yarn 94 would be the plating yarn.

Various changes in the shape, size, and arrangement of parts may be made to the form of invention herein shown and described, without departing from the spirit of the invention or the 75 scope of the claims.

I claim:

1. In cutting and binding mechanism for threads or yarns and the like the combination of means for cutting a thread or yarn, means to bind the thread or yarn at the time of the cutting operation, an auxiliary binding means cooperating with the first mentioned binding means to additionally bind the thread or yarn, said two binding means which cooperate in binding the 10 yarn being independently movable so far as the binding action is concerned and a single means to release said cutter and said binders.

2. In cutting the binding mechanism for threads or yarns and the like the combination of means for cutting a thread or yarn, means to bind the thread or yarn at the time of the cutting operation, an auxiliary binding means cooperating with the first mentioned binding means to additionally bind the thread or yarn, said two binding means which cooperate in binding the 15 yarn being independently movable and having independent spring means to actuate them in their binding effect upon the thread or yarn and a single means to release said cutter and said binders.

3. In a binder and cutter the combination of a cutter, a binder, a second binder, and means controlling said binders including a lost motion connection so that they may take independent binding effect on the same yarns.

4. In a yarn binder for knitting machines the combination of a main yarn binder, an auxiliary yarn binder for binding the same yarn as the main yarn binder, and means actuating said binders so that one takes binding effect ahead of 3 the other.

5. In a yarn binding mechanism for knitting machines and the like the combination of a main binder, means for actuating said main binder to a yarn binding position, an auxiliary binder for binding the same yarns as the main binder, and means for independently actuating the auxiliary binder to a yarn binding position.

6. In yarn binding and cutting mechanism the combination of a main binder for binding a given 4 yarn, an auxiliary binder for binding said given 4 yarn, a yarn cutter, and means for actuating said binders to a yarn binding position so that at least one of them takes binding effect upon said given yarn ahead of the cutter.

7. In a yarn binding and cutting mechanism the combination of a main binder for binding a given 4 yarn, an auxiliary binder for binding said given 4 yarn, a yarn cutter, and means for actuating one of said binders so that it takes binding effect upon said given yarn ahead of the other binder and ahead of the cutter.

8. Yarn binding mechanism for knitting machines comprising two independently movable 6 yarn binding devices for binding the same yarn and having means for actuating them to an open 6 yarn release position, and independent spring means for each of said binders for independently actuating them to a yarn binding position.

9. Yarn binding mechanism for knitting machines comprising two independently movable 6 yarn binding devices for binding the same yarn having pattern controlled means for actuating them to an open yarn release position, independent spring means for each of said binders for independently actuating them to a yarn binding position, and cutting means associated with the binders.

10. In yarn binding mechanism for knitting machines and the like the combination of a

- binding base having a yarn binding groove therein, a movable yarn binder operable against a side of said base for binding yarn, a movable yarn binder operable in the groove of said base for the additional binding of the same yarn or yarns, cutting means operable at the other side of the base from the first mentioned binder for the cutting of said yarns, and means actuating the second binder so that it takes binding effect upon the yarns ahead of the cutting action.
11. In a yarn binding mechanism for knitting machines and the like the combination of a binding base having a yarn binding groove therein, a movable yarn binder operable against a side of said base for binding yarn, a movable yarn binder operable in the groove of said base for the additional binding of the same yarn or yarns, cutting means operable at the other side of the base from
- the first mentioned binder for the cutting of said yarns, means actuating the second binder so that it takes binding effect upon the yarns ahead of the cutting action and first mentioned binder.
12. In a yarn binding and cutting mechanism the combination of a frame, a pair of pivoted binders on the frame having relatively independent pivot motion thereon, independent means for normally actuating them to a yarn binding position with respect to said frame, and a single means for opening said binders.
13. In a binding mechanism the combination of a binder frame, a binder pivoted on the frame, means including a lost-motion connection for moving the binder to an open position, and spring means normally urging said binder to a clamping position with respect to said frame.

- binding base having a yarn binding groove therein, a movable yarn binder operable against a side of said base for binding yarn, a movable yarn binder operable in the groove of said base for the additional binding of the same yarn or yarns, cutting means operable at the other side of the base from the first mentioned binder for the cutting of said yarns, and means actuating the second binder so that it takes binding effect upon the yarns ahead of the cutting action.
11. In a yarn binding mechanism for knitting machines and the like the combination of a binding base having a yarn binding groove therein, a movable yarn binder operable against a side of said base for binding yarn, a movable yarn binder operable in the groove of said base for the additional binding of the same yarn or yarns, cutting means operable at the other side of the base from
- the first mentioned binder for the cutting of said yarns, means actuating the second binder so that it takes binding effect upon the yarns ahead of the cutting action and first mentioned binder.
12. In a yarn binding and cutting mechanism the combination of a frame, a pair of pivoted binders on the frame having relatively independent pivot motion thereon, independent means for normally actuating them to a yarn binding position with respect to said frame, and a single means for opening said binders.
13. In a binding mechanism the combination of a binder frame, a binder pivoted on the frame, means including a lost-motion connection for moving the binder to an open position, and spring means normally urging said binder to a clamping position with respect to said frame.
